United States Patent

Des. 241,856

Patented Oct. 12, 1976

241,856

LISTENING CENTER

Jack H. Williams, 3229 W. Pioneer Drive,
Irving, Tex. 75061

Filed Sept. 17, 1975, Ser. No. 614,212

Term of patent 14 years

Int. Cl. D14—03; D19—07
U.S. Cl. D26—14 G

FIG. 1

FIG. 2

FIG. 3

FIG. 5

FIG. 4

FIG. 6

FIG. 1 is a perspective view of a listening center showing my new design;

FIG. 2 is a top plan view thereof;

FIG. 3 is a front view thereof;

FIG. 4 is a left side view thereof;

FIG. 5 is a right side view thereof; and

FIG. 6 is an elevational view of the listening center as viewed from a direction which is rotated 45° horizontally with respect to the view of FIG. 3.

The appearance of the listening center is the same when viewed from the top and the bottom.

The broken lines are shown for illustrative purposes only.

I claim:

The ornamental design for a listening center, as shown and described.
